[57] CLAIM

The ornamental design for a valve adaptor for LPG fuel tank, as shown and described.

DESCRIPTION

FIG. 1 is a front elevational view of the valve adaptor for LPG fuel tank showing my new design;

FIG. 2 is a side elevational view thereof, the other side being a mirror image;

FIG. 3 is a rear elevational view thereof;

FIG. 4 is a top plan view thereof; and

FIG. 5 is a bottom plan view thereof.

*Fig. 4**Fig. 2**Fig. 1**Fig. 3**Fig. 5*
